UNITED STATES PATENT OFFICE.

JAMES M. CUNNINGHAM, OF BETHANY, ILLINOIS.

RAIL-JOINT.

No. 927,830.

Specification of Letters Patent.

Patented July 6, 1909.

Application filed October 27, 1908. Serial No. 459,677.

To all whom it may concern:

Be it known that I, JAMES M. CUNNINGHAM, a citizen of the United States, residing at Bethany, in the county of Moultrie and State of Illinois, have invented certain new and useful Improvements in Rail-Joints; of which the following is a specification.

The present invention relates to improvements in railway rail joints, the object of the invention being the provision of a device for connecting the ends of adjoining rails of a railway track. In use the saddle, which constitutes the essential element of the invention, enables the railroad constructors to assemble and complete a joint of this character in a comparatively short time, and as the operation of assembling is simple, expert labor is not required. When in place, the improved joint affords a smooth and continuous connection between the rails thus preventing pounding by passing rolling stock, and as the joint provides the necessary elasticity, the wear upon the rolling stock is reduced to a minimum.

With these objects in view the invention consists in certain novel features of construction and combinations and arrangements of parts as hereinafter described, and more particularly pointed out in the claims.

In the accompanying drawings I have illustrated one example and a modification of the physical embodiment of the invention, constructed according to the best modes I have so far devised for the practical applications of the principles.

Figure 1 is a plan view of a portion of a railway track, for convenience, illustrating a pair of joints embodying the features of this invention. Fig. 2 is a transverse sectional view of a track as illustrated in Fig. 1. Fig. 3 is an enlarged view illustrating a rail and the joint plate or saddle. Fig. 4 is a perspective view of the saddle, and Fig. 5 is a sectional view illustrating a modified construction for anchoring the saddle or joint plate.

As in all approved types of rail joints the present invention contemplates the location of the joint plate or saddle 1 between a pair of ties 2, 2, and the ties are preferably recessed or cut away as at 3 to provide a seat upon which the bottom plate 4 of the saddle may rest, and the spikes 5 serve to firmly secure the saddle in place. The saddle is constructed of a shape to conform to the outline of the rails 6, being formed with top plates 7, 7 and vertical webs 8, 8 and these members

form the walls of a longitudinal channel which approximates the shape of the base and web of the rail.

In assembling the joint, the saddle is first secured to the ties, being seated in the recesses therein and secured by the spikes. The ends of the rails are then inserted, or rather the saddle is placed over the end of one rail, and the other rail end is inserted in the open end of the saddle. The ends are brought together to their proper location, and then the bolts are passed through the holes 10, 10 in the webs of the saddles, which in effect constitute fish-plates. A rail joint so constructed embodies many desirable features, and its simplicity lends effectiveness to its use. If desired I may omit the bolts 9, the countersunk saddle being sufficient connection between rails.

In Fig. 5 I have illustrated a modified form of construction, wherein the saddle is formed with tapered sides 11 which are adapted to dove-tail with the inclined sides 12 of a chair 13 which is countersunk into the tie and may be secured thereto by spikes, as indicated in dotted lines.

From the above description taken in connection with the drawings it is evident that I have produced a device which fulfills all the conditions set forth as the purpose and object of my invention.

What I claim as new and desire to secure by Letters Patent is:

1. The combination in a rail joint and with a pair of ties having each a recess, of a saddle adapted to rest in said recesses and secured to the ties, and the ends of the adjoining rails secured in said saddle said saddle extending longitudinally across two of the ties, and a pair of fastenings connecting the saddle with each tie arranged at an incline with reference to each other with the heads of the fastenings engaging the upper face of the saddles said saddles having the vertical portions which engage the web of the rail below the head and at the upper side of the foot and provide spaces on each side of the web.

2. The combination in a rail and with a pair of ties, of a saddle having a channel conforming to the outline of the base and web of rails secured therein, and means for securing the saddle to the ties said saddle extending longitudinally across two of the ties, and a pair of fastenings connecting the saddle with each tie and arranged at an incline with reference to each other with the heads of the

fastenings engaging the upper face of the saddles said saddles having the vertical portions which engage the web of the rail below the head and at the upper side of the foot and 5 provide spaces on each side of the web.

3. The combination in a rail joint and with a pair of ties, chairs countersunk in the ties having inclined walls, a saddle spanning the ties and having a dove-tail joint in said

chairs, and the ends of adjoining rails secured in said saddle. 10

In testimony whereof I affix my signature, in presence of two witnesses.

JAMES M. CUNNINGHAM.
